UNITED STATES PATENT OFFICE

GEORG KELLER, OF BERLIN-STEGLITZ, GERMANY

ARRANGEMENT FOR CONSECUTIVELY ADDRESSING ANY NUMBER OF ENVELOPES
WITHOUT CARBON COPY BY MEANS OF A TYPEWRITER

Application filed October 10, 1930, Serial No. 487,780, and in Germany October 9, 1929.

For dispatching letters and printed matter in most instances windowless envelopes are employed which must be addressed individually.

5 In the case of circularizing on a large scale the addresses are mostly copied by hand from a directory as the introduction of the envelopes into the typewriter takes too much time.

For the orderly delivery of a letter, it is 13 however better if the address is typewritten as it is more legible than handwriting which is often careless.

By means of this invention it is possible to address by means of a typewriter any number 15 of envelopes without carbon copy one after the other, that is without any loss of time by inserting separately each envelope to be addressed.

The invention consists in that the envelopes 20 to be addressed are connected directly or indirectly in a chain or band in such a manner, that the whole is fed into the typewriter and can be addressed consecutively without interruption.

25 The addressing of the envelope can be effected in this manner in the shortest imaginable time and absolutely legibly. At the same time the method makes it possible, by applying strips of gummed writing paper and carbon paper on the envelope to be addressed, to obtain further identically worded addresses which in the event of repeated sending of postal matter to the same addresses can be cut off in known manner and stuck 30 as labels on the envelopes in question.

Two embodiments of the invention are illustrated by way of example in the accompanying drawing in which:

Fig. 1 shows a back view of one form of 40 envelope in open condition.

Fig. 2 is a similar view to Fig. 1 showing a differently shaped envelope.

Fig. 3 shows the envelopes illustrated in Fig. 1 connected together like a band or chain.

Fig. 4 is a similar view to Fig. 3 of the envelopes shown in Fig. 2.

As shown in Figs. 1 and 2 the envelopes serving for carrying out the invention are 50 of the usual shape and size, but differ from

the ordinary envelopes in that the gummed portion *a* of the flap *b* does not extend to the point *c* or to the edge *d* of the flap but only up to a line of perforations *e* which separates the ungummed point *c* or edge *d* from the 55 gummed main portion of the flap *b*.

In order to produce a continuous band or chain-like unit according to Fig. 3 or 4 of envelopes to be written, the envelopes are connected together in such a manner that each 60 envelope covers about half the next following envelope. The outer side of the flap point *c* or of the flap edge *d* is stuck on the inner side of the flap *b* (Fig. 3) or edge (Fig. 4) of the envelope lying directly there- 65 under.

The envelopes are therefore connected in this manner in any desired number to form a band or chain shaped unit which is fed in this form into a typewriter and can continuously 70 be typed with addresses without any interruption, the envelope which has just been typed pulling along the chain of the envelopes still to be addressed when the typewriter machine is being shifted.

75 The band or chain shaped unit therefore preferably runs off a roll *f* in the manner shown in Fig. 5.

After the band has been typed with addresses, the individual envelopes are easily 80 severed along the perforations *e*.

If it is desired to send several dispatches to the same addresses, a suitable number of further addresses are preferably typed when addressing the envelopes, by placing a suitable 85 number of carbon and writing paper strips on the band or chain shaped row of envelopes (Figs. 3 and 4).

The uppermost strip will then be written directly by the typewriter, the strips situated thereunder as also the chain of envelopes being inscribed by means of carbon paper. The paper strips, which are preferably 90 gummed on the back, are then, after having been typed, cut into address labels and later 95 on simply stuck on the envelopes to be dispatched.

The connection of the individual envelopes to form a band or chain-shaped unit may 100 evidently be effected in any other suitable

manner, for example with the aid of one or more supporting bands.

I claim:

1. An arrangement for consecutively addressing any number of envelopes without carbon copies by means of a typewriter, comprising a plurality of envelopes arranged partly superposed to form a band, with the outside of the opened closing flap of one envelope stuck on the inner side of the preceding envelope.
2. An envelope for forming a band as specified in claim 1, comprising in combination with the envelope body, a closing flap 15 extending from said body gummed on the outer side at its extremity remote from said body adapted to be stuck to the inner surface of the preceding envelope.
3. An envelope for forming a band as 20 specified in claim 1, comprising in combination with the envelope body, a closing flap extending from said body, and an end portion of said flap gummed on its outer side adapted to be stuck on the inner surface of the preceding envelope and separated from said flap 25 by a row of perforations adapted to allow the envelope to be torn apart after the addressing.
4. An envelope for forming a band as 30 specified in claim 1, comprising in combination with the envelope body, a closing flap extending from said body gummed on its inner side along its edges, and an end portion of said flap gummed only on its outer side 35 adapted to be stuck to the inner surface of the preceding envelope.

In testimony whereof, I affix my signature.
GEORG KELLER.
